Primary Examiner — Susan E Krakower*Assistant Examiner* — Michelle M Reeves(74) *Attorney, Agent, or Firm* — Alan G. Towner; Leech Tishman Fuscaldo & Lampl**CLAIM**

The ornamental design for a hand sanitizer dispenser, as shown and described.

DESCRIPTION

FIG. 1 is an isometric top view of a hand sanitizer dispenser showing our new design;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

The broken lines in the drawings depict environmental subject matter and form no part of the claimed design.
